UNITED STATES PATENT OFFICE.

CHARLES G. HORNUNG AND HENRY WOLF, OF BUFFALO, NEW YORK.

METHOD OF FORMING BAIL-EARS ON SHEET-METAL VESSELS.

SPECIFICATION forming part of Letters Patent No. 694,644, dated March 4, 1902.

Application filed April 18, 1901. Serial No. 56,398. (No model.)

To all whom it may concern:

Be it known that we, CHARLES G. HORNUNG and HENRY WOLF, citizens of the United States, and residents of Buffalo, in the county 5 of Erie and State of New York, have invented new and useful Improvements in Methods of Forming Bail-Ears on Sheet-Metal Vessels, of which the following is a specification.

Our invention relates to a method of forming bail-ears on sheet-metal pails—such, for instance, as the well-known lard-pails. It is essential that the construction of the ears and the method of making and applying the same be simple, so that the pails can be provided with the ears at a low cost, that the parts be of a construction to permit the ready assembling and rapid attachment of the same, and that when the parts are attached the connection be a neat, permanent, and tight one. 15 The present invention is designed to fulfil these requirements.

In the accompanying drawings, which illustrate the parts on an enlarged scale, Figure 1 is a side elevation of a fragment of a pail-body, 20 showing one ear attached thereto. Fig. 2 is a cross-sectional view of the same in line 22, Fig. 1. Figs. 3, 4, and 5 show the parts separated. Fig. 6 shows the first step in the assembling of the parts. Fig. 7 shows the parts 25 assembled ready to receive pressure for interlocking the parts, as shown in Fig. 2.

Like letters of reference refer to like parts in the several figures.

The pail or vessel body *a*, of which a fragment is shown, has the opening *b* for the bail-ear bent with the edge inwardly to form a flange *c*. An internal groove *d* is preferably formed around the flange, forming a bead on the exterior of the body about the ear-opening *b*.

The cup-shaped ear *e* is of a diameter to snugly fit the ear-opening and is provided with a projecting flat base-flange *g*. This ear is provided in its crown with the usual central opening *h* to receive the hooked end of the bail. A locking-cap *i* completes the complement of parts to form the attachment. This cap is provided with a cylindrical peripheral flange or marginal wall *m* and is of such diameter as to fit snugly around the base-flange of the ear. The parts thus de-

scribed are shown in Figs. 3, 4, and 5 as they are turned out and before they are assembled.

In assembling the parts the ear *e* is preferably first seated in the cap *i*, as shown in Fig. 55 6, these parts fitting each other closely enough to remain connected by frictional contact. The ear is then inserted in the flanged opening from the inner side of the vessel and is pushed through until the edge of the flange 60 of the cap bears against the inner side of the vessel around the ear-opening, as shown in Fig. 7. The parts thus assembled are then placed between compression-dies *K L*, Fig. 7, the cap resting on the lower die *K* and 65 the upper die *L* bearing on the pail about the ear.

As the dies are forced toward each other the flanges of the opening and cap are bent or flattened, so as to interlock with each other. 70 The flange *m* of the cap is bent inwardly toward the flange of the opening along the inner surface of the body and the flange *c* of the opening is bent outwardly along the cap, and both flanges are tightly closed against 75 each other, as shown in Fig. 2. The inclined or curved surface of the groove *d* forms a guide for the edge of the cap-flange and greatly facilitates the bending of the same; but this groove is not indispensable, as a 80 pressure upon the edge of the flange will turn the flange toward the opening in any event. The flaring portion *e'* at the base of the ear *e* forms a guide which facilitates the turning of the flange of the opening. The flanges 85 of the opening and of the cap are thus tightly interlocked and pressed against the inner side of the vessel, around the opening thereof, and the base-flange *g* of the ear is firmly clamped between said interlocking flanges and the bottom portion of the cap. 90

We claim as our invention—

1. The herein-described method of securing a pail-ear to a vessel, consisting in forming an opening in the body of the vessel with an inwardly-extending straight flange, forming a pail-ear with an outwardly-extending base-flange, forming a cap with a straight marginal wall, assembling the parts with the marginal wall of the cap surrounding the base-flange 95 of the ear, and then inserting the ear in the opening in the body of the vessel, and finally 100

applying pressure to the parts to interlock said marginal wall and flanges, substantially as described.

2. The herein-described method of securing a pail-ear to a vessel, consisting in stamping an opening in the body of the vessel with a straight inwardly-extending flange and a surrounding groove, stamping out a pail-ear with a base-flange, stamping out a cap with a straight marginal wall, assembling the parts with the marginal wall of the cap surrounding the base-flange of the ear and then insert-

ing the ear in the opening in the body of the vessel and finally applying pressure to the assembled parts to interlock said marginal wall and flanges, substantially as described. 15

Witness our hands this 15th day of April, 1901.

CHAS. G. HORNUNG.
HENRY WOLF.
